E. H. TYLER.

Flyers for Covering Bonnet-Wire.

No. 140,322.

Patented June 24, 1873.

UNITED STATES PATENT OFFICE.

ERASTUS H. TYLER, OF ROCKVILLE, MASSACHUSETTS.

IMPROVEMENT IN FLIERS FOR COVERING BONNET-WIRE.

Specification forming part of Letters Patent No. 140,322, dated June 24, 1873; application filed April 11, 1873.

To all whom it may concern:

Be it known that I, ERASTUS H. TYLER, of Rockville, of the county of Norfolk and State of Massachusetts, have invented a new and useful Improvement in Bonnet Wires and Fliers for the making thereof; and do hereby declare the same to be fully described in the following specification, and represented in the accompanying drawings, of which—

Figure 1 is a top view, Fig. 2 a side elevation, and Fig. 3 a horizontal section, of one of my improved fliers. Figs. 4 and 5 are hereinafter explained.

The said flier is for winding in helical paths about the threads covering a bonnet metallic wire, or about a cord or pack of threads, two strands or threads of the same color or of different colors, or of the same kind of material, or of different kinds of materials. The flier is supported by and so as to be capable of revolving in a stationary tubular arbor, A, through which the bonnet-wire or article to receive the helical threads is to pass and be drawn with the necessary degree of velocity. The flier B consists of a tube, a, provided at one end with a whorl, b, and at the other with a counterbalanced bent arm, c, carrying an eye-piece, d, all being as represented. This eye-piece, near each of its ends, is provided with an eye or hole, e, having a lateral opening, f, through which the two threads from the bobbin, c, arranged upon the flier, as shown, may be passed into the eye. These threads represented at g h are led from the bobbin through the two eyes, and thence through two notches, i k, of an adjustable gage, D, fixed to an auxiliary arm, E, formed and arranged with the flier, and fixed thereto, as represented. This arm E is also notched, as shown at l, and the two threads are led through the notch and thence to the bonnet-wire to be bound, which runs parallel with and close to the auxiliary arm. The gage D is fixed to the arm E by a set-screw, l, going through a slot, m, all being so as to admit

of the gage being moved and adjusted in a lengthwise direction. As one thread will bear against the inner edge of the notch of the arm, and the other against the inner edge of the outer notch of the adjustable gage, it will be seen that, by moving the adjustable gage toward the end of the auxiliary arm, the two threads will be increased in distance asunder, the opposite result following the counter movement of the gage. Thus, by means of the adjustable gage and the auxiliary arm, made as described, the distance apart of the threads wound on the wire or its substitute may be regulated.

Bonnet-wire as heretofore made has, so far as I have been able to discover, had but one binding-thread wound helically about the longitudinal threads covering the metallic wire. As a consequence, the breakage of such binding-thread would loosen the covering-threads held by it, and thus be productive of evil consequences, especially in case of the wire being sewed through the covering-threads to an article. With a bonnet-wire having two helical binding-threads wound about it, should one become cut or broken the other will generally remain intact, and hold the covering-threads in place.

Fig. 4 is a side view, and Fig. 5 a transverse section on an enlarged scale, of a piece of such bonnet-wire. In this figure, a is the metallic body, b b b the longitudinal covering-threads, and g h their two helical binding-threads, such being the article produced by the flier hereinbefore described, it being understood that the longitudinal threads are applied to the metallic wire by such means as are usually adopted.

I claim—

The combination of the adjustable gage D and the auxiliary arm E, substantially as described, with the flier B, to operate as explained.

ERASTUS H. TYLER.
